CIRCUIT INTERRUPTER

James M. Wallace, East McKeesport, and Alvin W. Ogg, Pittsburgh, Pa., assignors to Westinghouse Electric Corporation, East Pittsburgh, Pa., a corporation of Pennsylvania

Continuation of application Serial No. 540,192, June 14, 1944. This application July 27, 1948, Serial No. 40,958

11 Claims. (Cl. 200—89)

1

This invention relates to electric circuit interrupters in general, and, more particularly, to circuit interrupters which automatically operate to reclose the circuit following a circuit interrupting operation, with this application being a continuation of our application Serial No. 540,192, filed June 14, 1944, on the same subject and assigned to the same assignee as this invention.

In circuit interrupters of the type having electroresponsive means for separating the interrupter contacts which are biased into engagement in order to automatically reclose the circuit, a pumping action of the contacts has been encountered under conditions where the electrical condition to which the contact separating means responds is relatively small. These conditions cause an initial separation of the contacts, but before the contacts can separate any appreciable amount, interruption occurs and the contacts immediately reclose, usually before time delay means provided for controlling the speed of reclosure, and before integrating means usually provided for preventing more than a predetermined number of successive reclosings, can operate. If such a relatively small electrical condition persists, the contacts will continue to rapidly open and close, and this not only results in excessive arcing, but no opportunity is given for such a condition to clear itself. What may happen then is that the pumping action continues until the interrupter destroys itself.

One object of this invention is to prevent pumping in a circuit interrupter of the type described, by providing novel means actuated by electroresponsive means for causing the interrupter contacts to separate at least a predetermined distance on each circuit opening operation which is sufficient to introduce a predetermined time delay before the circuit is reclosed.

Another object of this invention is to provide in an automatic reclosing circuit interrupter of the type described, overcenter spring means adapted to be operated over center by electroresponsive means to open the interrupter contacts at least a predetermined amount on each circuit opening operation.

One complication that arises in providing any means for obtaining at least a predetermined amount of contact separation at a predetermined rate independent of the rate of movement or force exerted by electroresponsive actuating means, is that the amount of contact separation varies in some interrupters with the value of current interrupted. In other words, the greater the current interrupted, the greater the separation of the contacts. In order to accommodate such variable contact separation, it is necessary that the circuit opening means be associated with

2

the contacts in a manner to permit them to operate free of the opening mechanism, at least on interruption of high currents.

Accordingly, another object of this invention is to provide in an automatic reclosing circuit interrupter of the type described, novel means actuated by electroresponsive means for causing the interrupter contacts to separate at least a predetermined amount on each circuit interrupting operation, with provision for further separation of the contacts independent of the opening means.

Another object of this invention is to provide in an automatic reclosing circuit interrupter, separable contacts which are held closed under predetermined contact pressure, and electroresponsive means to separate the contacts by first storing energy at a rate determined by the magnitude of the electrical condition to which it responds, and then releasing the stored energy when a predetermined amount of energy has been stored to rapidly separate the contacts at least a predetermined amount on each circuit interrupting operation.

Another object of this invention is to provide snap-acting mechanism directly engaging the movable contact of a circuit interrupter to open the circuit with a snap action, wherein the mechanism releases the movable contact after predetermined opening movement of the contact to permit continued opening movement of the movable contact independent of the mechanism.

The provision of a means for obtaining at least a predetermined amount of contact separation on each circuit interrupting operation in a circuit interrupter of the type which automatically recloses after each circuit interrupting operation, also requires provisions for resetting the opening means so that on a succeeding circuit interrupting operation, the same predetermined contact separation will be obtained.

Accordingly, still another object of this invention is to provide in an automatic reclosing circuit interrupter, means for obtaining at least a predetermined contact separation on each circuit opening operation of the interrupter, with novel means responsive to automatic reclosure of the interrupter to reset the circuit opening means so that the same predetermined contact separation will be obtained on the next succeeding interrupting operation.

These and other objects of this invention will become more apparent upon consideration of the following detailed description of preferred embodiments thereof when taken in connection with the attached drawings, in which:

Figure 1 is a side elevation view of an automatic reclosing circuit breaker constructed in

accordance with this invention, with part of the breaker casing broken away to illustrate the interior construction, some of which is shown in section;

Fig. 2 is an enlarged, partial elevational view of the breaker operating mechanism shown in Fig. 1 looking from the left of Fig. 1;

Fig. 3 is a side elevation view of the mechanism shown in Fig. 2, with the parts at the position occupied when the breaker contacts are open;

Fig. 4 is an elevational view, partially in section, of a modified form of actuating mechanism for use with a circuit breaker like that shown in Fig. 1;

Fig. 5 is a partial elevational view of the mechanism shown in Fig. 4, looking from the right of Fig. 4;

Fig. 6 is a partial side elevation view of still another modified form of breaker operating mechanism; and

Fig. 7 is another elevation view of the mechanism shown in Fig. 6, but with the parts located at the position they occupy when the breaker contacts are open.

The circuit breaker shown in Fig. 1 is preferably mounted in a tubular casing 2 of insulating material, such, for example, as porcelain or the like. The casing 2 may be mounted on a support by means of a bracket 4 secured about the casing substantially at the mid-portion thereof. The casing 2 is preferably provided with a closed bottom which is apertured for the reception of a terminal bolt 6 having an enlarged head 8 adapted to be seated on a gasket 16 with in casing 2. A nut 10 is adapted to secure the terminal bolt in position, and also to secure a terminal strap 12 in conductive relation with the bolt, so that a line conductor may be electrically connected therewith by means of a terminal socket 14. The top of casing 2 is preferably open, and a cover casting 18 is seated on the open top of casing 2. Cover casting 18 preferably has a flange adapted to seat on gasket 20 provided on the top of casing 2, and the cover casting may be secured to casing 2 in any desired manner, such, for example, as by securing means (not shown) connecting the cover casting and an anchor ring 22. Preferably anchor ring 22 is secured at the upper end of casing 2 by means of cast metal 24 or the like, interlocking ring 22 with grooves provided in the outer surface of the casing.

Cover casting 18 is provided with a hollow portion 26 which is open to the interior of casing 2, and has a shaft 28 extending across the hollow space to be rotatably mounted at its opposite ends in opposite walls of the cover casting. A generally U-shaped spring support 30 has the leg portions thereof rotatably mounted on shaft 28, and the spring support 30 is biased to rotate in a counterclockwise direction by a coil compression spring 32. A spring supporting rod 34 is provided for spring 32, with the spring mounted on the rod and reacting between a collar 36 fixed to supporting rod 34, and an apertured ear 38 provided integral with the cover casting. The spring supporting rod 34 is pivoted to spring support 30 as at 40, so that in biasing rod 34 to the left, as viewed in Fig. 1, the spring support 30 is biased to rotate counterclockwise. Normally counterclockwise rotation of spring support 30 is prevented by an overcenter toggle comprising a link 42 pivotally connected with the spring support as at 46, and with another toggle link 44 by a pivot 48. Toggle link 44 is pivotally mount-

ed in the cover casting as at 50, and is provided with an integral extension 52 which is normally held by spring 32 in engagement with an adjustable stop screw 54 threadedly mounted in a hood portion 56 integral with cover casting 18. Extension 52 of toggle link 54 is provided at its outer end with a hook-eye aperture 60 for the reception of a hook-stick operating member or the like.

Spring support 30 is also adapted to cooperate with a coil spring 62 wound about shaft 28, with one end 64 of the spring engaging spring support 30, and the other end 66 thereof engaging an actuating crank 68 pivotally mounted on shaft 28. Actuating crank 68 is adapted to be connected by a pair of links 70 of insulating material, such, for example, as fiber or the like, with a head 164 fixed on the upper end of a contact actuating rod 76. The connecting links 70 are pivoted to actuating crank 68 as at 72, and to head 164 by pivot pin 74.

The breaker contacts are mounted in the lower portion of casing 2 within an arc chamber 78 formed by a cylindrical tube 80 of insulating material, such as fiber or the like, having a top cap 62 threadedly mounted on one end thereof, and a bottom cap 84 threaded on the other end thereof. A current-carrying compression spring 86 is adapted to be compressed between a shoulder provided on the bottom cap of arc chamber 78 and head 8 of terminal bolt 6, to carry current from the lower terminal of the casing to the bottom cap of arc chamber 78. Bottom cap 84 of the arc chamber is provided with a central opening for receiving a contact screw 88, which is secured in operative position by a lock nut 90. Bottom cap 84 of the arc chamber is also provided with spaced inlet apertures 92, which may be covered by a valve disk 94 loosely mounted in the lower part of the arc chamber. A stop ring 96 is clamped between bottom cap 84 of the arc chamber and the lower end of tubular member 89, for a purpose to be described. The top cap 82 for the arc chamber is provided with a plurality of outlet apertures 98, adapted to be controlled by a valve plate 100, normally biased to uncover the outlet apertures by a compression spring 102.

The lower end of contact actuating rod 76 is provided with a contact tip 104 secured thereto, and it has a contact head 106 at the lower end thereof for engagement with contact screw 88 in the closed position of the circuit breaker. A liquid director 108 is slidably mounted on contact tip 104, and in the closed circuit position is biased against stop ring 96 by a compression spring 110 reacting between the contact actuating rod 76 and the liquid director.

In service, casing 2 is preferably filled with an arc-extinguishing liquid up to a level located at the upper end of the casing adjacent ring 22. Accordingly, the arc chamber is submerged in such liquid, and will be filled with arc-extinguishing liquid at all times. It will be noted that in the structure described above, the movable contact 106 is continuously biased towards stationary contact 88, so that whenever there is no force exerted on contact 106 tending to move it away from contact 88, biasing spring 62 will cause engagement of the contacts and consequent closure of the circuit. If movable contact 106 be separated from fixed contact 88, an arc will be formed within arc chamber 78 which will act on the arc-extinguishing fluid therein to produce gases and build up a pressure within the arc-

extinguishing chamber. This pressure within chamber 78 causes valve disk 94 and valve plate 100 to seal to inlet and outlet openings, and the pressure will act on the movable contact rod in a piston-like manner to cause further separation of the contacts. This separation of the contacts will continue until the arc is extinguished. As soon as the arc is extinguished within arc chamber 78, the pressure will decrease, and outlet openings 98 will be uncovered by movement of valve plate 100 downwardly under the influence of spring 102. This permits the escape of gases from the arc chamber and permits inflow of fresh liquid through inlet openings 82, so that a flushing of the arc chamber will automatically occur after each circuit interrupting operation.

It will be observed that the contact closing bias of spring 62 may be destroyed and the breaker contacts opened, by collapsing toggle levers 42 and 44, as by rotating toggle lever extension 52 in a clockwise direction. This moves toggle links 42 and 44 overcenter, and permits spring 32 to move spring support 30 counterclockwise thus removing the support for the end 64 of biasing spring 62. Rotation of spring support 30 in a counterclockwise direction by spring 32, also causes it to engage the end 69 of crank 68 and hold it in a position wherein contact 106 is out of engagement with fixed contact 88. Obviously, the toggle levers 42 and 44 may be moved overcenter back to the position shown in Fig. 1, by merely rotating the toggle extension 52 in a counterclockwise direction back to the position shown in Fig. 1. This will relatch spring support 30 in the position shown, and permit biasing spring 62 to close the breaker contacts.

Preferably, contact actuating rod 76 is provided with a sleeve of insulating material 112 within arc chamber 80 which covers the actuating rod in its passage through the top cap 82 of the interrupter chamber. This sleeve of insulation serves to separate the contact actuating rod from a tubular core 114 of magnetic material, which is adapted to be attracted by a solenoid coil 118 mounted in a supporting frame 116 secured to the upper end of the arc chamber. The supporting frame 116 preferably has at least one side thereof open to permit insertion of the solenoid coil 118, which is annular in form. A dashpot cylinder sleeve 120 is centrally mounted in supporting frame 116, and serves to properly locate coil 118, and is secured in position in alignment with apertures through the top and bottom of frame 116 by a collar 122, threaded into the aperture through the top of frame 116. Dashpot cylinder 120 is provided with an integral inwardly extending stop flange 126, for limiting upward movement of tubular core 114. Core 114 is connected at its upper end with the lower end of an actuating sleeve 130 slidably mounted on actuating rod 76, and the two sleeves are normally biased downwardly by a coil compression spring 124 reacting between collar 122 and the juncture between the sleeves. Collar 122 is preferably provided with a restricted vent aperture 128 for limiting the rate at which fluid escapes from dashpot cylinder 120.

The upper end of actuating sleeve 130 is provided with a collar 132 for connection to a contact actuating mechanism supported between spaced supporting plates 134, preferably secured at their upper ends to cover casting 18, and joined at their lower ends, by a connecting strap 136, to solenoid supporting frame 116, preferably in insulated relation, as by washers of insu-

lating material (not shown) interposed between plates 134 and cover casting 18. The contact actuating mechanism includes a generally U-shaped lever 138 pivotally mounted as at 140 on supporting plates 134, and connected with collar 132 of actuating sleeve 130, by a pair of connecting links 142 pivoted to the collar as at 146 and to the U-shaped lever as at 144. Lever 138 is adapted to control an overcenter tension spring 148, having one end hooked over a pin 151 on the lever, and the other end hooked over a pin 150 mounted between generally triangular-shaped links 152. The triangular-shaped links 152 are preferably joined at one side by an integral connecting strip 153, and are pivotally mounted on extensions 155 of supporting plates 134, as at 154. The triangular-shaped links 152 are connected with an actuating collar 160 which is slidably mounted on actuating rod 76, by means of a pair of connecting links 156, pivotally connected with links 152 as by a pivot pin 158, and pivotally connected with the actuating collar as at 162.

The electrical circuit through the circuit breaker shown in Fig. 1 extends from the cover terminal 19 through bracket 17, cover 18, through a conductor 163 to solenoid coil 118, then by way of a flexible conductor (not shown) to contact actuating rod 76, to fixed contact 88, compression spring 86, terminal bolt 6, to terminal 14. Solenoid coil 118 is, therefore, connected in series in the circuit through the interrupter so that upon the passage of current through the circuit above a predetermined value, the solenoid will attract core 114 with sufficient force to cause it to move upwardly at a rate determined by the rate of escape of liquid through dashpot vent 128. This upward movement of solenoid core 114 causes lever 138 to be moved in a counterclockwise direction about its supporting pivot 140, and tensions overcenter spring 148. As soon as spring 148 is moved in a counterclockwise direction past the center line of spring supporting pin 150 and pivot 154 for the triangular-shaped links, the spring will then exert a force on the triangular-shaped links in a direction to cause clockwise movement of these links about their pivots 154, and thereby cause upward movement of connecting links 156 and sliding of actuating collar 160 along the contact actuating rod into engagement with head 164, to thereby cause movement of contact 106 away from fixed contact 88. It will be observed that no force is applied to separate the contacts until spring 148 is moved overcenter, when the full force of the stressed spring is suddenly exerted to separate the contacts against the bias of their biasing spring 62. The amount of contact separation produced by overcenter spring 148 may obviously be regulated any desired amount. However, this amount should be sufficient to obtain at least a predetermined amount of contact separation such that an appreciable delay occurs before the contacts are reclosed by biasing spring 62. This is accomplished by the use of the mechanism described by storing energy in overcenter spring 148 during the first part of the movement of solenoid core 114, and then suddenly releasing this energy to separate the contacts, so that the rate of contact separation and the distance of separation will be entirely independent of the rate of movement of the solenoid core, or the force developed by solenoid coil 118.

As soon as the contacts separate, an arc is established between them and pressure developed thereby will exert an additional contact-separat-

ing force the value of which depends upon the current value of the arc. The position of the overcenter spring and parts associated therewith is shown in Fig. 3 of the drawings, when these parts have moved to the positions they occupy when the contacts are separated. It will be observed that because there is lost motion of actuating collar 160 on the contact operating rod, that after the contacts are separated the amount predetermined by actuation of overcenter spring 148, movable contact 104 may then further separate from fixed contact 88 by sliding movement of contact actuating rod 76 in actuating collar 160. However, as soon as the arc is extinguished, solenoid coil 118 will be deenergized, and biasing spring 62 will then be free to reclose the contacts. If movable contact 106 has travelled beyond the position the contact actuating rod occupies in Fig. 3, biasing spring 62 will quickly restore it to the position shown in Fig. 3. However, it will be noted that further reclosing cannot occur because the toggle comprising connecting links 156 and triangular links 152 is held at an overcenter position by spring 146. However, solenoid core 114 and actuating sleeve 130 will then be slowly returned to their normal position by compression spring 124, the rate of return being determined by the size of vent 128 for dashpot cylinder 129. This results in gradual movement of lever 138 in a clockwise direction, and it eventually moves spring 148 back below pivot 154, to thereby break the toggle holding the contacts open and thus assist biasing spring 62 in rapidly reclosing the contacts.

In order to limit the number of successive circuit interrupting operations which can take place in the event a continuing fault appears on the circuit, there is provided integrating means for counting the number of closely succeeding circuit interrupting operations, preferably mounted on a support 166 secured to supporting plates 134. The support 166 carries a cylindrical tube 168 in which is mounted an integrator piston 170 having notches 172 therein which are accessible through a side opening in the upper end of tube 168, so as to be engaged by an actuating pawl 174. Pawl 174 is generally U-shaped in form, and has the lower leg thereof apertured to be slidably mounted on a guide rod 176 also secured on support 166, and has the upper leg slotted to receive the guide rod, but permitting tilting of the upper end of the pawl into and out of engagement with notches 172. A coil compression spring 178 mounted on the guide rod is adapted to normally maintain the pawl in the position shown, where it is out of engagement with integrator piston 170.

In the operation of the circuit breaker, each time lever 138 is moved in a counterclockwise direction to its upper position designated by dotted line 181, it engages pawl 174 and moves it upwardly on guide rod 176. The engagement of lever 138 with pawl 174 also causes the upper end of the pawl to enter a notch 172 in the integrating piston, and move the piston upwardly with the pawl an amount roughly equal to the distance between notches 172. Support 166 is provided with a fluid-inlet opening 180 for cylinder 168, which permits flow solely inwardly by virtue of a ball-check valve seated over opening 180 within tube 168. Upon reclosure of the circuit breaker following an interrupting operation, pawl 174 is returned to its original position shown in Fig. 1 by spring 178, while integrator piston 170 remains at the position to which it has been advanced, returning very slowly to its

original position shown in Fig. 1 due to the necessity of displacing liquid which has been drawn into the bottom of tube 168 past the relatively small clearance between the piston and tube 168. If after the reclosing operation the fault has cleared, piston 170 will eventually sink to its original position. However, if the fault or overload condition is still present upon reclosure of the circuit breaker, it will immediately reopen, and this time pawl 174 will engage the next lower notch 172 on the integrator piston. This will cause the piston to be raised upwardly a further amount, substantially into engagement with toggle link 44. Upon the second closely succeeding reclosure of the breaker, if the overload condition has disappeared, the integrator piston will again slowly sink to its original position. However, if the overload condition is still present on the circuit, the breaker will again open immediately, and this time pawl 174 will engage the lowest notch in the integrator piston, and move the piston upwardly until extension 182 thereof engages toggle link 44 and moves it upwardly to collapse toggle links 42 and 44, and thereby permit spring 32 to rotate spring support 30 in a direction to maintain the breaker contacts open, and render reclosing spring 62 inoperative. This, of course, will be accompanied by movement of extension 52 of toggle link 44 downwardly, so that it will project below hood 56 and present a readily visible indication of the locked-open condition of the breaker.

In the embodiment of the invention shown in Figs. 4 and 5, contact head 106 is adapted to engage a stationary contact which has some resiliency to provide the necessary contact pressure. Preferably, this is accomplished by a stationary contact structure which includes a contact bolt 184 having a head 190 thereon, with the bolt secured in position by a nut 186. A contact cup 192 is telescoped over the head 190 of bolt 184, and is normally biased toward the movable contact by a compression spring 194, which is maintained in compressed condition when the contacts are closed, as shown in Fig. 4.

In this embodiment of the invention, actuating sleeve 130 which is attached to the solenoid core, is connected by links 142 with levers 198, as by pivot pins 196. The levers 198 are pivoted at their opposite ends on supporting pins 200, and an overcenter spring 202 is connected at one end with pivot pin 196, and at its other end engages a pin 204 connecting generally triangular-shaped links 206. The triangular-shaped links 206 are pivotally mounted on a fixed support as at 208, and are connected to movement multiplying levers 216, by connecting links 210, pivoted to the triangular links as at 212, and to the levers 216 as by a pivot pin 214. The levers 216 are supported by a pivot pin 218, and are connected to contact actuating rod 76 by links 222, pivoted to levers 216 as at 220, and to the contact actuating rod by a pivot pin 224.

It will be noted that in the closed position of the contacts, overcenter spring 202 maintains the toggle comprising levers 206 and 210 at an overcenter position against a fixed stop 211. This holds the contacts in engagement with contact pressure spring 194 compressed a predetermined amount to provide a predetermined contact pressure. When an overload condition appears on the circuit and the solenoid core is attracted upwardly to move links 142 upwardly and levers 198 in a counterclockwise direction, spring 202 will be placed under further tension,

but the contact pressure will be unchanged due to the extended overcenter condition of toggle levers 206 and 210. Eventually spring 202 will be moved past pivot point 208, whereupon it will be effective to rotate links 206 in a clockwise direction, and thus break the toggle formed by levers 206 and 210. Thus, pressure is maintained at a predetermined value on the contacts until after spring 202 moves over the center of pivot point 208, and as soon as this occurs, clockwise rotation of the links 206 induced by the spring will cause connecting links 210 to be pulled upwardly and levers 216 to rotate in a counterclockwise direction, thereby moving connecting links 222 upwardly to move contact 106 away from contact cup 192. This means that predetermined pressure is maintained on the contacts until actual contact separation occurs.

Toggle levers 42 and 44' may also be provided in connection with this embodiment of the invention for maintaining the breaker contacts in open circuit position when the toggle is broken, and in this instance, toggle lever 44' is preferably provided with an integral extension 226, which engages with adjustable stop screw 54, to maintain the toggle in extended condition under the stress of coil spring 234, which reacts at one end against a fixed support 238, and at its other end against a pin 236 on crank 230 pivotally connected with toggle lever 42 as at 231. Crank 236 is pivotally mounted on fixed pivot 232. A hook eye 228 is provided in the outer end of extension 226, for permitting manual operation and resetting.

Since contact pressure, in the embodiment of the invention shown in Figs. 4 and 5, is maintained by the operating mechanism and by overcenter spring 202, but a relatively weak spring 240 need be employed to effect a reclosing operation, since all this spring needs to do is to move spring 202 back overcenter to the position shown in Fig. 4. Accordingly, reclosing spring 240 is mounted on a guide rod 242 pivotally connected at one end with levers 198 as by a pivot pin 244, and having a slot 246 in its other end for receiving pivot pin 231 of toggle link 42. Spring guide rod 242 is provided with collars 248 between which spring 240 reacts, to normally bias levers 198 in a clockwise direction.

After a circuit opening operation, and when the solenoid becomes deenergized due to extinguishing of the arc, spring 240 will then be free to rotate levers 198 in a clockwise direction to move spring 202 back overcenter toward the position shown in Fig. 4. This movement, however, will be resisted by the dashpot action of the solenoid core, so that a predetermined time delay will be inserted between circuit interruption and reclosure of the breaker contacts.

In the embodiment of the invention shown in Figs. 6 and 7, contact actuating rod 76 is provided with an actuating pin 250 secured thereto, which is adapted to be actuated by an actuating link 252, having an open-ended slot with one short side 256, and a long side 254, for receiving pin 250 therebetween. The movement of actuating lever 252 is controlled by a supporting link 258 pivotally connected with the actuating link as at 259, and pivoted on a support as at 262. The supporting link 258 preferably is provided with an integral, laterally extending stop flange 260, for a purpose to be described. Movement of the actuating link 252 is also controlled by a second link 264 pivotally connected with the actuating link as by a pivot pin 266, and mounted on

5 a support by means of the pivot pin 200. The actuating link 252 is operated by means of an overcenter compression spring 268 mounted within a tubular spring housing 270, which is pivotally mounted on pivot pin 266, and has the other end thereof slotted as at 274, for receiving an actuating pin 272 provided on lever 198.

10 In the operation of the embodiment of the invention shown in Figs. 6 and 7, it is apparent that in the closed circuit position (Fig. 6), spring 268 assists the reclosing spring in holding the contacts closed. In opening the circuit, lever 198 is moved upwardly in a counterclockwise direction in the same way as in the embodiment of the invention shown in Figs. 4 and 5. This causes compression of overcenter spring 268, until the spring passes over pivot point 259, whereupon supporting lever 264 is moved downwardly in a clockwise direction, this causes pivotal movement of actuating link 252 in a counterclockwise direction about its pivot 259 to thereby move contact actuating rod 76 upwardly to separate the breaker contacts. Continued clockwise rotation of supporting link 264 finally causes movement of actuating link 252 away from pin 250 at least enough to clear the upper leg 256, to the position illustrated in Fig. 7 where actuating link 252 engages stop flange 260. At this position, it is clear that contact actuating rod 76 may continue its circuit opening movement, and have overtravel with respect to the overcenter spring and its actuating linkage, any desired amount. However, when the circuit has been interrupted, and contact actuating rod 76 returns toward closed circuit position, pin 250 will engage lower leg 254 of the actuating link, and further closing movement will be delayed by the dashpot action of the solenoid core connected with links 142, until overcenter spring 268 is moved back overcenter toward the position shown in Fig. 6.

45 In all the embodiments of the invention disclosed, means are provided for preventing pumping action of the breaker contacts by requiring at least a predetermined amount of contact separation, at a predetermined rate, irrespective of the rate of movement of the electroresponsive actuating means, or the amount of force generated thereby. Thus, on very low current overloads, the contacts will be separated at least a predetermined distance and at a predetermined rate of speed sufficient to allow enough time delay before reclosure to permit clearing of the fault, if it be of the self-clearing type, and to prevent too rapid opening and reclosing of the breaker contacts. At the same time, the minimum contact separation provided is so arranged as to always actuate the integrating counting mechanism so that upon a predetermined number of closely succeeding circuit interrupting operations, the breaker contacts will be maintained in open circuit position. In general, this is accomplished by the provision of overcenter spring actuating mechanism moved in the direction to open the circuit by electroresponsive means, and in the opposite direction by a reclosing spring. In accordance with this invention, the contact actuating mechanism may be associated with the movable contact in such a manner as to permit overtravel of the contact with respect to the mechanism, for example, as by the lost motion connection in the species of Figs. 1 to 3, or by the releasable connection in the species of Figs. 6 and 7. Moreover, the contact actuating mechanism embodying an overcenter spring may utilize such spring to maintain pre-

determined pressure on the breaker contacts until they are actually separated, and in lieu of a heavy reclosing spring, a relatively light spring may be used merely to reset the overcenter spring mechanism.

Having described preferred embodiments of the invention in accordance with patent statutes, it is desired that the invention be not limited to these particular embodiments, because it will be obvious to persons skilled in the art that many modifications and changes may be made in these particular embodiments without departing from the broad spirit and scope of this invention.

We claim as our invention:

1. An automatic reclosing circuit breaker comprising, separable contact means one of which is mounted for movement into and out of engagement with the other, operating means for said movable contact means comprising, electro-responsive means which is movable in response to a predetermined electrical condition of the circuit to separate said contact means and interrupt the circuit, overcenter spring means interposed between said electroresponsive means and said movable contact means so as to be moved overcenter in response to such movement to separate said contact means, means responsive to a circuit opening operation for automatically reclosing said contact means, means actuated by said overcenter spring in response to movement thereof overcenter in one direction for counting closely successive operations of said breaker, and means operated by said counting means in response to a predetermined number of closely successive breaker operations for preventing reclosure of the breaker contacts.

2. An automatic reclosing circuit breaker comprising, separable contact means one of which is mounted for movement into and out of engagement with the other, operating means for said movable contact means comprising, electro-responsive means which is movable in response to a predetermined electrical condition of the circuit to separate said contact means and interrupt the circuit, means interposed between said electroresponsive means and said movable contact means which is normally operable to provide a predetermined pressure between said contact means and is responsive to the aforesaid movement of said electroresponsive means to store energy during the first part of such movement and thereafter release such energy to separate said contact means, means dependent upon the current value of the arc formed upon separation of said contacts to exert additional contact-separating force on said movable contact means to thereby obtain a contact opening speed which varies from a minimum determined by said stored energy on low currents in accordance with the value of current interrupted, a lost motion connection between said interposed means and said movable contact means so that said movable contact means may have overtravel relative to said interposed means during a circuit opening operation, and means responsive to a circuit opening operation for automatically reclosing said contact means.

3. An automatic reclosing circuit breaker comprising, separable contacts, electroresponsive means movable in one direction in response to a predetermined electrical condition of the circuit for causing separation of said contacts, toggle means comprising a pair of toggle levers pivotally connected together at one end of each lever to form a knee pivot, one of said levers having a

lost motion connection at a remote point to one of said contacts, the other of said levers being pivoted at a remote point on a stationary support so as to be movable to one overcenter position to separate said contacts, and into engagement with a stop member to lock the contacts at an open circuit position, and a spring connected between said toggle means and said electroresponsive means so as to be moved overcenter in one direction in response to predetermined movement of said electroresponsive means to move said toggle means to its said one overcenter position to separate said contacts and lock said contacts separated at least a predetermined distance apart, means responsive to a circuit opening operation to move said spring overcenter in the other direction to permit automatic reclosure of said contacts, and time delay means for delaying the last-mentioned movement of said overcenter spring.

4. In an automatic reclosing circuit breaker, separable contacts, electroresponsive means having lost motion with respect to said contacts so as to be movable in response to a predetermined electrical condition of the circuit a predetermined distance before causing separation of said contacts, said contacts being biased in a direction to automatically reclose in response to a circuit interrupting operation and to provide a predetermined contact pressure when closed, a spring connecting said electroresponsive means and one of said contacts and adapted to be moved overcenter in response to predetermined movement of said electroresponsive means to separate said contacts at least a predetermined distance and at a rate independent of the rate of movement of said electroresponsive means and the amount of force exerted thereby, means independent of said closing bias to move said spring overcenter in the opposite direction to permit reclosure of said contacts, and time delay means for delaying movement of said spring overcenter at least in one direction.

5. In an automatic reclosing circuit breaker, separable contacts, electroresponsive means movable in response to a predetermined electrical condition of the circuit for causing separation of said contacts, said contacts being biased in a direction to automatically reclose in response to a circuit interrupting operation, a spring adapted to be moved overcenter in response to predetermined movement of said electroresponsive means to separate said contacts at least a predetermined distance and at a rate independent of the rate of movement of said electroresponsive means and the amount of force exerted thereby, said spring having a connection with at least one of said contacts which is separable in response to said predetermined contact separation to permit overtravel of said contacts in a circuit interrupting operation independent of said spring and electroresponsive means and means operable to effect overtravel of said contacts in accordance with the current value of an arc formed upon separation of said contacts.

6. In an automatic reclosing circuit breaker, separable contacts, electroresponsive means movable in response to a predetermined electrical condition of the circuit for causing separation of said contacts, said contacts being biased in a direction to automatically reclose in response to a circuit interrupting operation, and spring means interposed between said electroresponsive means and said contacts and normally operable to provide a predetermined pressure between said contacts.

tact means and is operable in response to predetermined movement of said electroresponsive means to first store and then release a predetermined amount of energy which is at least greater than the force biasing said contacts closed, to separate said contacts at least a predetermined distance and at a rate independent of the rate of movement of said electroresponsive means and the amount of force exerted thereby, said interposed means having a connection with at least one of said contacts which is separable in response to said predetermined contact separation to permit overtravel of said contacts in a circuit interrupting operation independent of said spring means and electroresponsive means.

7. In an automatic reclosing circuit breaker, separable contacts, electroresponsive means having lost motion with respect to said contacts so as to be movable in response to a predetermined electrical condition of the circuit a predetermined distance before causing separation of said contacts, said contacts being biased in a direction to automatically reclose in response to a circuit interrupting operation and to provide a predetermined contact pressure when closed, a spring connecting said electroresponsive means and one of said contacts and adapted to be moved overcenter in response to predetermined movement of said electroresponsive means to separate said contacts at least a predetermined distance and at a rate independent of the rate of movement of said electroresponsive means and the amount of force exerted thereby, and means independent of said closing bias and connected to said spring to move said spring overcenter in the opposite direction to permit reclosure of said contacts.

8. In an automatic reclosing circuit breaker, separable contacts, electroresponsive means movable in response to a predetermined electrical condition of the circuit for causing separation of said contacts, said contacts being biased in a direction to automatically reclose in response to a circuit interrupting operation, a spring adapted to be moved overcenter in response to predetermined movement of said electroresponsive means to separate said contacts at least a predetermined distance and at a rate independent of the rate of movement of said electroresponsive means and the amount of force exerted thereby, said spring having a connection with at least one of said contacts which is separable in response to said predetermined contact separation to permit overtravel of said contacts in a circuit interrupting operation independent of said spring and electroresponsive means, and said separable connection being automatically reestablished by reclosure of said contacts to move said spring overcenter in the opposite direction.

9. In an automatic reclosing circuit breaker, separable contacts, electroresponsive means movable in response to a predetermined electrical condition of the circuit for causing separation of said contacts, said contacts being biased in a direction to automatically reclose in response to a circuit interrupting operation, a movable actuating member for said contacts having a pin and open-end slot connection with at least one of said contacts, an overcenter spring actuated by said electroresponsive means for moving said actuating member at least in a circuit opening direction, means guiding the movement of said actuating member so as to cause separation of said contacts a predetermined distance during the

first portion of its movement and thereafter cause movement of said actuating member so as to permit escape of said pin from the open end of said slot upon continued separation of said contacts, and means to cause said pin to reenter said slot in response to reclosure of said contacts to cause movement of said spring overcenter in the opposite direction.

10. In an automatic reclosing circuit breaker, separable contacts, electroresponsive means movable in response to a predetermined electrical condition of the circuit for causing separation of said contacts, a movable actuating member for said contacts having a pin and open-end slot connection with at least one of said contacts, an overcenter spring actuated by said electroresponsive means for moving said actuating member at least in a circuit opening direction, means guiding the movement of said actuating member so as to cause separation of said contacts a predetermined distance during the first portion of its movement and thereafter cause movement of said actuating member so as to permit escape of said pin from the open end of said slot upon continued separation of said contacts, and means to cause said pin to reenter said slot in response to reclosure of said contacts to cause movement of said spring overcenter in the opposite direction.
11. An automatic reclosing circuit breaker comprising, separable contacts, electroresponsive means movable in one direction in response to a predetermined electrical condition of the circuit for causing separation of said contacts, toggle means connected between one of said contacts and a stationary support so as to be movable to one overcenter position to separate said contacts, and into engagement with a stop member to lock them at an open circuit position, a spring connected between said toggle means and said electroresponsive means so as to be moved overcenter in one direction in response to predetermined movement of said electroresponsive means to move said toggle means to its said one overcenter position to separate said contacts and lock said contacts separated at least a predetermined distance apart, and resilient means stressed by said electroresponsive means during the aforesaid predetermined movement thereof for moving said spring overcenter in the other direction to permit automatic reclosure of said contacts.
